UNITED STATES PATENT OFFICE.

CROMWELL P. WEAVER, OF PHILADELPHIA, PENNSYLVANIA.

MODE OF HANGING WINDOW-SASH.

Specification of Letters Patent No. 15,447, dated July 29, 1856.

To all whom it may concern:

Be it known that I, CROMWELL P. WEAVER, of the city of Philadelphia and State of Pennsylvania, have invented a new and Improved Mode of Hanging Window-Sashes; and I do hereby declare the following is a full, clear, and exact description of the same, reference being had to the accompanying drawing and to the letters of reference 10 marked thereon.

My invention consists in so connecting window sashes to bars arranged to slide in recesses in the jambs of the window frame, that the said sashes may be removed and re- 15 placed with facility.

In order to enable others skilled in the art to make and use my invention I will now proceed to describe its construction and operation.

20 On reference to the drawing which forms a part of this specification Figure 1, is an elevation (looking from the inside of a window frame, with sashes hung in my improved mode; Fig. 2, the same as Fig. 1, 25 with part of the frame removed; Fig. 3, a side view in section on the line 1—2 Fig. 2; Fig. 4, a transverse sectional plan, of part of the frame the sashes being both up; Fig. 5, a top view of part of the frame and sashes, 30 with the lintel removed; Fig. 6, a perspective view of the sliding bar for one sash and Fig. 7, a perspective view of the sliding bar for the other sash. Figs. 4, 5, 6, and 7, are drawn to an enlarged scale.

35 The same letters of reference allude to similar parts throughout the several views.

The frame of the window consists of the lintel A the two hollow jambs B, B, and the sill C. The side pieces b and b' of the 40 jambs project beyond the cross piece c so as to form a recess for receiving the sliding bars D and E which together fit accurately, but so as to move freely, therein.

On each of the sliding bars D is a projecting strip d one end of which fits with a shoulder against the side b of the jamb, the other end forming a lip against which rests the side of the sash F. On the top of each of the sliding bars D is secured a light metal 50 lip e which projects a slight distance over the top of the sash F when the latter is in its place, it has also a metal strip f at the bottom, and on this rests the bottom of the sash.

55 Each of the sliding bars E has a project-

ing strip h against which bears the sash G it has also on the top a light metal lip i which projects over the top of the said sash when the latter is in its place, and also a metal strip j on which the sash rests. 60

On the bottom bar of the sash F (see Fig. 3) is a projection l against which bears the sash G, and the latter has a similar projection k at the top bearing against the sash F. The bottom sash G has a spring latch m on each side the point of which fits an orifice in the flange of the metal strip j on the bottom of the sliding bar E from which the latches can be withdrawn and replaced at pleasure. Each of the sliding bars E has a tongue n 70 which fits in a groove in the cross piece e of the hollow jamb.

Each of the sliding bars D has a projecting bracket p to which one end of the cord R is connected. This cord passes upward and over a pulley T then downward and around the pulley S then upward and over the pulley H then downward again until it reaches a projection v on the sliding bar E to which projection the cord is attached. 75 The pulleys H and T run loose on pins attached to a plate which is secured permanently to the cross-pieces c of the hollow jambs, and the pulley S is hung on a pin in a staple projecting from the counter-balance weight I. 80

The sliding bars D and E being placed in the recesses formed on the inside of the jambs, and the cords connected to the same as described, the two bars are first slid up to 90 the top as seen in Fig. 3, the sash F is then put into its place by inclining it so as to catch the metal strips e it is then easily pushed home so that the bottom of the sash rests on the strip f; the sash G is now connected to the sliding bars F in a similar manner, and the points of the spring latches m allowed to catch into the holes in the strip j. The sashes are now perfectly secure in their 95 respective sliding bars, and the latter equally 100 as well secure in their recesses in the jambs.

It will be seen that the sashes can be easily removed by simply withdrawing the spring latches, and that without the trouble attending the removal of sashes hung in the ordinary manner, in which case the sash beads have to be ripped off and consequently more or less mutilated. It will also be seen that by the peculiar arrangement of cords, pulleys, and weights in connection with the slid- 105 110

ing bars, the latter with their sashes are always balanced at whatever point they are raised or lowered to.

I do not claim the employment of a single weight for the balancing of sashes; but

What I do claim and desire to secure by Letters Patent, is—

The employment in connection with window frames and sashes of the sliding bars

D and E the same being arranged and constructed substantially in the manner herein set forth for the purpose of removing and replacing said sashes with facility.

C. P. WEAVER.
